FIG. 5.

UNITED STATES PATENT OFFICE.

JOHN HUDRY, OF HAZLETON, PENNSYLVANIA.

SPRING BED-BOTTOM.

1,101,934.

Specification of Letters Patent. Patented June 30, 1914.

Application filed May 22, 1912. Serial No. 699,049.

To all whom it may concern:

Be it known that I, JOHN HUDRY, a citizen of the United States, residing at Hazleton, in the county of Luzerne and State of Pennsylvania, have invented a certain new and useful Improvement in Spring Bed-Bottoms, of which the following is a full, clear, and exact description.

The object of this invention is to provide 10 a spring bed bottom of simple, economical and durable construction, for use in connection with bedsteads, cribs, or other similar articles of furniture.

The invention consists in a bed bottom 15 constructed of a series of spaced longitudinal and transverse strips of thin sheet metal placed one upon the other and provided at their crossings with complementary slots and lugs for securing said strips together, all 20 substantially as I will proceed now to set forth and finally claim.

In the accompanying drawings, illustrating 25 the invention, in the several figures of which like parts are similarly designated, Figure 1 is a plan view. Fig. 2 is a perspective view, on a larger scale, of a portion of the bed bottom, and Fig. 3 is a longitudinal section; Fig. 4 is a transverse section, and Fig. 5 is a bottom plan view, on a still 30 larger scale, of one of the connections at the crossings of the strips.

The bed bottom of the present invention, is designed to be supported in a frame of any suitable or approved construction, and 35 as shown in Fig. 1, such a frame may comprise side rails 1 and end rails 2, and corner fastenings 3 for engaging complementary fastenings on the head and foot of the bed.

The bed bottom proper comprises the 40 longitudinal strips 4, of thin, flat, sheet metal, suitably spaced apart and having at suitably spaced intervals throughout their length, slots 5, preferably rectangular in shape, punched or cut therethrough, and 45 provided at their opposite ends with eyes or openings 6, and transverse strips 7, of similar material, placed upon said longitudinal strips over the slots 5 therein, and having punched or cut out portions or lugs 50 8 coinciding with said slots 5, and adapted to be bent down through the slots and then

bent upwardly against the underside of the longitudinal strips 4, as shown more clearly in Figs. 3, 4 and 5, thus securely locking the strips 4 and 7 together at their crossings. 55 Preferably, the opposite ends 9 of the transverse strips 7 are bent around the outer edges of the outer longitudinal strips 4, as more clearly shown in Fig. 2. The bed bottom as thus constructed is supported in 60 the frame 1, 2, by coiled springs 10 having their terminals connected with the eyes 6 in the ends of the longitudinal strips 4 and with the end rails 2 of the frame. Any other suitable spring connections may be 65 used for connecting and supporting the bottom in the frame instead of the coiled springs as herein shown.

I have herein shown the slots 5 in the longitudinal strips and complementary cut 70 out portions 8 of the transverse strips for engaging said slots, oblong in shape, but I do not wish to be understood as limiting the invention to this particular shape of such parts, as the same may be constructed 75 of any other suitable, but preferably angular, shape.

By this construction a very simple, durable and economical bed bottom is provided, and by the angular shape of the connections 80 between the longitudinal and transverse strips, twisting or turning of the strips one upon the other at their crossings is avoided, thus rigidly maintaining the strips in substantial parallelism. 85

What I claim is:—

1. A spring bed bottom, comprising a series of spaced longitudinal strips of thin, flat sheet metal and a series of spaced transverse strips of similar material crossing each 90 other and provided with complementary angular slots and integral lugs at the points of crossing, said lugs passing through said slots and bent upon the opposite sides of the strips, to thereby rigidly secure the 95 strips together at their points of crossing.

2. A spring bed bottom, comprising a series of spaced longitudinal strips of thin, flat sheet metal and a series of spaced transverse strips of similar material crossing each 100 other and provided with complementary angular slots and integral lugs at the points

of crossing, said lugs passing through said slots and bent upon the opposite sides of the strips, to thereby rigidly secure the strips together at their points of crossing, and
5 said transverse strips having their ends bent around and under the outer edges of the outermost longitudinal strips.

In testimony whereof, I have hereunto set my hand this 21st day of May 1912.

JOHN HUDRY.
